UNITED STATES PATENT OFFICE.

JOSEPH F. D. HOGE, OF NEW YORK, N. Y., ASSIGNOR TO WESTERN ELECTRIC COMPANY, INCORPORATED, OF NEW YORK, N. Y., A CORPORATION OF NEW YORK.

ALTERNATING-CURRENT RELAY.

Application filed May 11, 1922. Serial No. 560,101.

To all whom it may concern:

Be it known that I, JOSEPH F. D. HOGE, a citizen of the United States, residing at New York, in the county of New York, State of New York, have invented certain new and useful Improvements in Alternating-Current Relays, of which the following is a full, clear, concise, and exact description.

10 This invention relates to relays designed to selectively respond to currents of a desired frequency.

An object of the invention is to so mount the relay as to render its operation independent of all jars or shocks.

15 A further object of the invention is to improve the means for adjusting the contacts of the relay, and to maintain such contacts in an adjusted position.

20 More specifically, the invention relates to a relay which is so mounted upon rubber sponges by means of washers and stud screws that there will be a certain allowable play between the base plate of the relay and its mounting surface. The relay which is designed to operate, say at a frequency of 135 cycles, has its adjusting means placed in such a position as to be readily accessible when it becomes necessary to correct any deviation of the vibrating relay reed from its desired operation. Furthermore, the improved locking means provided for holding this adjusting device in its desired position, is so designed as to permit exceedingly accurate adjustments of the relay to be obtained and to lock these adjustments without in any way disturbing the adjustment obtained. No tools are required for the adjusting or locking means.

35 40 In the drawings, Fig. 1 is a perspective view, partly in section, of the preferred modification of the invention, while Fig. 2 is a side elevation partly shown in section.

45 Referring to the drawings in detail, an alternating current relay having a base plate 1 is mounted upon a metallic mounting 2 which has attached thereto a series of plugs 3 to adapt the relay for rack mounting. A flange or a handle 4 integral with the mounting 2 facilitates the handling of the relay. Rubber sponges 5, held in place by ears 6 which are integral with the mounting 2, are placed between the base plate 1 of the relay and the mounting. Other

50 mounting 2 in alignment with the two intermediate sponges by means of disk washers 7 and stud screws 8 which are threaded into the relay base plate 1. This method of mounting relieves the relay of unnecessary jarring and furthermore facilitates removal and renewal of the sponges or other shock absorbing means, should such means become fatigued.

55 The relay proper comprises a conducting block 9 having mounted thereon a metallic bar 10 which is separated from block 9 by insulation 11. A vibrating reed 12 has its one end fixedly mounted in the conducting block 9 and its other end free to move between the pole pieces of two electromagnets 13 and 14 which are located on either side thereof. A follow-up spring 15, which cooperates with the vibrating reed 12, is similarly attached to the bar 10, its other end being free to move with vibrating reed 12. A small weight 16 which is attached to the free end of the follow-up spring 15 engages a rubber covered stop 17 in the course of its vibrations, the stop serving to limit 60 the amplitude of the spring's vibrations.

65 A spiral spring 22 is attached at one end to the follow-up spring and at its other end to an adjusting rod 18 by means of a fibre thread 23. This spring serves as a 70 means for varying the tension upon follow-up spring 15.

75 The adjusting rod 18 is rotatably mounted at its one end on bar 10 and has its other end journaled into a supporting post 19. 80 A shoulder 20 attached to adjusting rod 18 engages supporting post 19 and serves to limit the end play of the rod 18. Adjusting knob 21 spaced from shoulder 20 is rigidly attached to one end of the rod 18 and serves 85 as an accessible means for adjusting the angular position of this rod. A locking member 24 is pivotally mounted upon the post 19 and is provided with a lip 25 which is free to move between the shoulder 20 and knob 21 of the adjusting rod 18. A set screw 26 is threaded into the locking member 24, the end of the screw engaging post 19 when the screw is turned to force the 90 lower portion of the locking member 24 100 away from the post 19 at the same time bringing the lip 25 into close engagement with the shoulder 20 of the adjusting rod 18. By means of this arrangement, it is possible to so vary the friction between the 105 110

lip 25 and the shoulder 20 that the adjusting rod 18 may be turned to any desired position without having the spiral spring 22 exert sufficient tension to draw the 5 rod back to its original position. When the desired position is thus obtained, it is possible by turning the set screw 26 a few degrees to apply a sufficiently greater friction to the shoulder 20 to securely lock the 10 member 18 without disturbing its adjusted position.

The operation of the relay is as follows: Alternating current passing into the electromagnets 13 and 14 causes the vibration 15 of the reed or armature 12. The armature being stiff and of comparatively heavy stock has a natural period of vibration of approximately 135 cycles per second so that a small current of this same frequency passing 20 through the coils 13 and 14 will set such armature into motion. The spring 15 being of very much lighter stock and having a weight attached to its end has a low natural period of vibration so that when the armature 25 12 is set in motion the spring 15 is struck and caused to swing toward the post 17, and since it has a low period of vibration will open the circuit normally closed through these members. Fundamentally 30 the operation of this relay is similar to the operation of the relay shown and described in the patent to Fell, No. 708,539, September 9, 1902.

When the adjusting knob 21 is turned in a clockwise direction the coil spring 22 will tighten and raise the tension in the follow-up spring 15. By varying this tension the period of vibration of spring 15 may be changed so that the effective opening of the 40 contact between spring 15 and armature 12 during the operation of the relay may be varied so as to be sufficient for the purpose for which the relay is designed.

What is claimed is:

45 1. A relay having an armature, a tensioning device, and means for controlling said tensioning device comprising a rod having a shoulder integral therewith, and a locking device having a lip for engaging 50 said shoulder for rendering said means inoperable.

55 2. A relay having a flexible armature, a tensioning device for said armature, and means for controlling said tensioning device comprising an accessible member having a shoulder integral therewith, and a pivoted locking member for engaging said shoulder to render said first named means inoperable.

60 3. A relay having a flexible armature, a tensioning device for said armature, and means for controlling said tensioning device comprising an accessible member having a shoulder integral therewith, and a pivoted locking member for engaging said

shoulder to render said first named means inoperable.

4. A relay having a flexible armature, a tensioning device for said armature, a support, a member cooperating with said support, said member having a shoulder integral therewith, and a pivoted locking member having a lip, a threaded member cooperating with said locking member and said support to force said lip into engagement 75 with said shoulder.

5. A relay having a flexible armature, a tensioning device for said armature, a support, means for varying the tensioning of 80 said device comprising a member journaled in said support, said member having a shoulder integral therewith, and a pressure varying member for engaging said shoulder to render said first named member inoperable.

6. A relay having a flexible armature, a tensioning device for said armature, a support, a rotatable member journaled therein serving to vary the tension of said device, 90 said member having a shoulder, and an adjusting knob integral therewith, said shoulder and said knob being spaced from each other, a pressure varying member having a lip disposed between said shoulder and said knob, and serving to restrict said rotatable 95 member.

7. In a relay, a flexible armature, a support, a rod journaled in said support and having a shoulder integral therewith, a tensioning member between said armature and said rod and controlled by the rotation of 100 said rod, a pressure varying member pivotally mounted upon said support comprising a friction member, and means for forcing said friction member into engagement with said shoulder.

8. In combination, a support, a rotatable member journaled therein, said member having a knob integral therewith for varying 110 its angular position, and means for locking said member comprising a pivoted bar having a lip for engaging said knob, and means to tilt the lip of the pivoted member into frictional engagement with said knob.

9. In combination a support, a rotatable member journaled therein, said member having a shoulder integral therewith, an adjustable knob spaced from said shoulder, means for locking said member comprising 115 a pivoted bar having a lip disposed intermediate said shoulder and said adjustable knob to frictionally engage said shoulder, and a member threaded in said pivoted member and engaging said support to tilt said lip into engagement with said shoulder.

10. In combination, a body portion, a block mounted thereon, an armature having one end thereof secured to said block, a resilient member having one end secured to 120 said block and having its other end free

- to cooperate with said armature, electro-
magnetic means secured to said body portion
and serving to actuate said armature and
said resilient member, a support on said
5 body portion, a rotatable member journaled
in said support and having an adjustable
knob integral therewith, tensioning means
disposed between said resilient member and
said rotatable rod, and locking means pivot-
10 ally mounted on said support for friction-
ally engaging said adjustable knob to render
the rotating member inoperable.
11. A resiliently mounted relay comprising
15 a body portion and a base plate, elastic
material between said body portion and said
base plate, means for holding said material
in place, a support secured to said base plate,
- an armature having one end secured to said
support, a flexible follow-up spring having
one end attached to said support, said spring 20
cooperating with said armature to operate
the relay, a U-shaped support attached to
said base plate, a pair of pole pieces mounted
on said support and serving to actuate
said armature and said spring, a post, a 25
rotatable member journaled in said post and
having an adjustable knob integral therewith,
a locking member pivotally secured to
said post, said member engaging the knob to
render said rotating member inoperable. 30

In witness whereof, I hereunto subscribe
my name this 8th day of May A. D., 1922.

JOSEPH F. D. HOGE.
